UNITED STATES PATENT OFFICE.

OTTO MUELLER, OF CHICAGO, ILLINOIS, AND WILLIAM D. HAMER, OF INDIANAPOLIS, INDIANA, ASSIGNEES TO ELECTRIC SERVICE SUPPLIES COMPANY, OF PHILADELPHIA, PENNSYLVANIA, A CORPORATION OF NEW JERSEY.

SUPPORT FOR ELECTRIC CONDUCTORS.

1,246,304.

Specification of Letters Patent. Patented Nov. 13, 1917.

Application filed January 21, 1915. Serial No. 3,447.

To all whom it may concern:

Be it known that we, OTTO MUELLER and WILLIAM D. HAMER, citizens of the United States, and residents, respectively, of Chicago, in the county of Cook and State of Illinois, and Indianapolis, in the county of Marion and State of Indiana, have jointly invented an Improved Support for Electric Conductors, of which the following is a

specification.

Our invention is an electric conductor support adapted to be applied to the tops of poles, and it is characterized by the desiderata that it is simple, strong, balanced, readily installed securely, applicable to sections of different thicknesses without injurious cutting, and designed to hold conductors in symmetrical relation, in different vertical planes, so that vertical and lateral pressures are carried economically and efficiently while short circuiting is avoided in case of broken conductors.

The improvements characteristic of our invention will more fully appear from the following description and the accompanying drawings in illustration thereof.

In the drawings, Figure 1 is an elevation of a support embodying our improvements in operative position, and Fig. 2 is a plan view of the same below the line 2—2 of Fig. 1.

The support, in the form thereof here selected for the purpose of illustrating the invention, comprises the angle iron cross-arm 1 having its median section bent laterally so that its leg or web 1^a shall be exterior to the arch produced and its leg or web 1^b shall have a flat, comparatively extended bearing against the pole 2 with the ends of the arm in alinement with the center of the pole, the legs of the angle providing the desired resistance to vertical and lateral bending stresses. A yoke 3, preferably formed of strap iron approximately the width of the leg 1^a, comprises the flat crown 3^a, the diverging similar sections 3^b extending transversely thereto, the approximately parallel similar sections 3^c extending from the sections 3^b, the diverging similar sections 3^d extending from the sections 3^c, and the flanges 3^e extending outwardly in a common plane from the free ends of the sections 3^d. The yoke is fixed in transverse relation to the cross arm by securing the flanges 3^e to the web 1^a, on its side opposite the web 1^b,

by means of bolts 4, placed equally distant from the ends of the cross-arm.

The yoke is fixed on the top of the pole, symmetrically with reference to the axial plane thereof, by fitting the expanded ends of the sections 3^b to the end of the pole and the sections 3^c to opposite sides thereof, and passing the bolts 5 transversely through the pole and the parts 3^c. The cross bar is fixed in place by passing the bolt 6 through the web 1^b and the post 2 transversely to the bolts 5.

The insulator 7 is fixed to the crown 3^a by the bolt 8, centrally with reference to the support and pole, the open space between the parts 2, 3^a and 3^b permitting free manipulation for this purpose. The insulators 9 are fixed to the ends of the arm 1, on the web 1^a, by the bolts 10 passing therethrough outside of the bolts 4 at points equidistant from the bolt 6 at the center of the arm.

Since the parts 1^b and 3^c can be fitted to the pole by shaving the wood with the grain, if any cutting is required, this operation is readily effected, without exposing the cross section of the grain to the weather and the timber to decay, which takes place where transverse cutting is required to fit certain forms of supports.

As the parts of the support, including the insulators, are symmetrically arranged with reference to an axial plane, the load carried will be balanced, and as the insulators are in different vertical planes a broken conductor carried by one of them will not fall across a conductor carried by another with resulting short circuiting.

The transverse dispositions of the bolts and webs, together with the arrangement of the diagonals 3^b and 3^d so that each is adapted to take both tension and compression, provides the appliance with superior strength and capacity for taking both vertical and lateral pressure efficiently.

Having described our invention, we claim:

1. The combination of a cross-arm having an arched median section with a web bent laterally to form a curved bearing surface and a bent stiffening web exterior to the bend of said web first named, with a yoke having oppositely inclined diagonal parts fixed to said web second named, approximately parallel parts fixed to the respective diagonal parts, and a crown for connecting said ap-

proximately parallel parts and supporting an object.

2. The combination of a cross-arm having an arched intermediate section adapted to

5 fit a pole with said arm disposed transversely thereto, and a yoke having a crown, diverging sections connected with said crown, sections connected with said diverging sections and adapted to fit longitudinally against opposite sides of said pole, and

10 diverging sections connected with said second named sections and fixed to said cross-arm.

3. The combination with a pole, of a cross-arm having a bent seat engaging said pole, a yoke having sections engaging opposite sides of said pole longitudinally, a part con-

nected with said sections across the end of said pole, and diagonal members diverging from said sections and fixed to said arm on 20 opposite sides of said seat.

In testimony whereof, we have hereunto set our names this 31st day of December, 1914, in the presence of the subscribing witnesses.

OTTO MUELLER.
WILLIAM D. HAMER.
